UNITED STATES PATENT OFFICE

161,751

HOLDER FOR PLAYING CARDS

Jacob L. Haring, Glen Rock, N. J.

Application April 4, 1950, Serial No. 8,977

Term of patent 7 years

(Cl. D34—13)

To all whom it may concern:

Be it known that I, Jacob L. Haring, a citizen of the United States of America, and resident of Glen Rock, county of Bergen and State of New Jersey, have invented a new, original, and ornamental Design for a Holder for Playing Cards, of which the following is a specification, reference being had to the accompanying drawing, forming a part thereof, wherein:

Fig. 1 is a plan view of a holder for playing cards, showing my new design;

Fig. 2 is a side elevation view of the holder; and

Fig. 3 is an end elevation of the holder.

I claim:

The ornamental design for a holder for playing cards, substantially as shown.

JACOB L. HARING.
